UNITED STATES PATENT OFFICE

157,144

SHOE RACK

Robert E. Grindinger and Nona F. Grindinger,
Kansas City, Mo.

Application August 25, 1948, Serial No. 148,283

Term of patent 14 years

(Cl. D33—8)

To all whom it may concern:

Be it known that we, Robert E. and Nona F. Grindinger, citizens of the United States, residing at 3816 Walnut Street, city of Kansas City, county of Jackson, State of Missouri, have invented a new, original, and ornamental Design for a Shoe Rack, of which the following is a specification, reference being had to the accompanying drawing, forming a part thereof, wherein:

Fig. 1 is a front elevational view of a Shoe Rack, showing my new design.

Fig. 2 is a top plan view thereof.

Fig. 3 is an end elevational view thereof.

We claim:

The ornamental design for a shoe rack, as shown.

ROBERT E. GRINDINGER.
NONA F. GRINDINGER.
